UNITED STATES PATENT OFFICE.

LAMBERT SCHMIDT, OF WEEHAWKEN, NEW JERSEY.

TELEPHONE SYSTEM.

SPECIFICATION forming part of Letters Patent No. 660,124, dated October 23, 1900.

Application filed March 8, 1900. Serial No. 7,785. (No model.)

To all whom it may concern:

Be it known that I, LAMBERT SCHMIDT, a citizen of the United States, residing in Weehawken, county of Hudson, State of New Jersey, have invented certain new and useful Improvements in Telephone Systems, of which the following is a specification, reference being had to the accompanying drawings, forming a part hereof.

10 This invention relates to intercommunicating telephone systems in which each party calling makes connection at his own station or instrument with the station or instrument of the party called. In such systems there

15 are at each station open connections for the several lines to the other stations or instruments in the system. The party calling commonly makes the desired connection by the insertion of the plug at the proper point. It

20 has also been proposed to arrange the series of contacts or terminals of the several lines so that a movable contact or switch-arm may sweep over the same, such switch-arm being held by a suitable detent on the desired contact or terminal and being released by the hanging up of the receiver, so that it may return to its initial position.

This invention is more particularly concerned with automatic switches of the class 30 to which that just referred to belongs; and it has for its object to overcome certain difficulties which are developed in the practical use of such automatic switches as that referred to. Thus it has been sought to provide a device which can be completely inclosed, so that the contacts shall be protected from dust. It has also been sought to provide a device which shall be free from the difficulties incident to the use of a single switch-arm sweeping over a series of contacts, it having been found difficult to give such an arm a sufficient bearing upon the fixed contact or terminal without interfering with its freedom of movement to such an extent as to render its return to initial position when released somewhat uncertain.

A further object has been to facilitate the work of making the necessary connections when the instrument is set up.

40 The invention will be more fully described and its nature explained hereinafter with ref-

erence to the accompanying drawings, in which—

Figure 1 is a perspective view of a calling and receiving instrument or telephone set to 55 which the improved automatic switch is applied. Fig. 2 is a plan view of the improved switch adapted for use in a single-wire system, the casing being shown in section. Fig. 3 is a front elevation of the same with the 60 casing in section. Fig. 4 is a section on the plane indicated by the broken line 44 of Fig. 3. Fig. 5 is a diagram illustrating the electrical connection. Fig. 6 is a view similar to Fig. 2, but illustrating the application of the 65 switch to a two-wire system. Fig. 7 is a detail view of the construction shown in Fig. 6, illustrating the manner in which the connections are formed. Fig. 8 is a detail section on the plane indicated by the broken line 88 70 of Fig. 6, and Fig. 9 is a diagram illustrating the electrical connections when the switch is applied to a two-wire system.

In the embodiment of the invention represented in the drawings a shaft or drum A is 75 mounted in the ends of suitable bearings in the supporting-frame B and is provided outside of the casing C, which entirely incloses the shaft or drum and other parts hereinafter referred to, with a knob or handle A', by which 80 it may be rotated. A spring a' is connected to the shaft or drum and to the frame, so as to return the former to its initial position when it has been turned forward and is released. There is also secured to the shaft or 85 drum a ratchet-wheel A², which is engaged by a pawl a² to hold the shaft or drum in whatever position of rotation it has been set against the force of the spring a'. An ordinary hook-lever D, which is extended through 90 the casing C and is adapted to support the usual receiver R, rests upon the tail of the pawl a², so that when the receiver is applied to the hook, as usual when the telephonic communication has been completed, its added 95 weight acting in opposition to the pawl-spring will disengage the pawl from the ratchet-wheel and so permit the shaft or drum to be rotated backward to its initial position by the spring a'. At a convenient point on the shaft 100 or drum is secured an indicator-wheel A³, having a broad rim A⁴, upon which are formed

or secured the numbers or other designations of the several stations of the system, such numbers or other designations being visible one at a time through a sight-opening *c* in the 5 casing *C*. Secured to the shaft or drum *A* and disposed spirally about the same are pins *a*, which correspond, respectively, to the several stations of the system. The relative arrangement of the several pins, the several 10 teeth of the ratchet-wheel *A*², and the several numbers on the indicator-wheel is such that when any number is visible at the sight-opening the corresponding tooth of the ratchet-wheel is then engaged by a pawl and the corresponding pin *a* is then in operative position. 15 As shown in Fig. 2, the indicator-wheel may be provided with a stop *a*³, projecting inward from the rim *A*⁴, to limit the backward rotation of the shaft and determine the initial 20 position of the parts by engagement with a fixed stop *b*.

All of the parts above referred to are found in both constructions represented in the drawings—namely, the construction which is 25 adapted for application to a single-wire system and the construction which is adapted for application to a two-wire system—and the operation of such parts as far as described is the same in both cases. In the single-wire 30 system, however, the circuit-closing pins *a* are themselves included in the circuit, while in the two-wire system the circuit-closing pins are not included in the circuit, but operate to close the circuit between two separated 35 contacts. It will be obvious that the invention is substantially the same in both cases so far as concerns the structure already referred to. Such differences as characterize the two applications of the switch will now 40 be pointed out.

Referring first to the arrangement shown in Figs. 2, 3, and 4, it will be observed that the shaft or drum *A* is connected in the calling-circuit and that each of the pins *a* thereon 45 is likewise in the calling-circuit. Supported in convenient position adjacent to the shaft or drum *A* are spring contacts or terminals *E*, each one of which is insulated from the others and from the frame and is connected 50 electrically with the corresponding calling-wire. These contacts or terminals are preferably secured alternately to opposite sides of the supporting-frame. By this arrangement I secure greater compactness than would 55 be possible if the contacts or terminals were all arranged on one side of the frame. It will therefore be seen that whenever the shaft or drum *A* is rotated to bring a certain station-indicator to the sight-opening the 60 corresponding circuit-closing pin *a* will be brought into contact with the corresponding spring contact or terminal *E* and will be held there by the engagement of the pawl with the corresponding tooth of the ratchet-wheel. 65 The first act of the party calling is of course to remove the receiver from the hook-lever,

which leaves the pawl free to engage the ratchet-wheel, and the next act is to establish connection with the desired line by the 70 rotation of the shaft or drum *A*. The release of the hook-lever breaks the circuit through the bell or other signal *S* and completes the circuit through the circuit-closing device already referred to and the receiver and transmitter. The usual push-button *P* 75 is operated to throw current from the ringing-battery on the line for the purpose of calling the attention of the party whose line has been brought into circuit, and conversation is then carried on. When communication 80 has been completed, the receiver is hung again upon the hook-lever, which restores the line to its normal condition in readiness for a call and releases the rotating switch or shaft *A* to be returned immediately by the 85 spring *a'* to its initial position.

In the application of the switch to a two-line or all-metallic system (illustrated in Figs. 6, 7, 8) and 9, the pins *a* on the shaft or drum *A* operate to close the desired circuit, but do not themselves form parts of such circuit. Secured upon the frame in positions corresponding with the several circuit-closing pins *a* on the shaft or drum are double pairs of contacts or terminals, each 90 pair consisting of an upper contact *e'* and a lower contact *e*², the upper contact of each pair being connected with the corresponding leg of the corresponding line, while the lower contact of each pair is connected with the 95 corresponding leg of the home wire of the station. The pin *a* has a head sufficiently broad to engage both of the lower contacts and lift them against the upper contacts, thereby establishing connection between the 100 home line and the particular line desired. The operation of the push-button *P* throws current on the ringing-circuit of the station called, as already described with reference to the arrangement shown in Fig. 5, and in 105 other respects, except as hereinbefore indicated, the operation of the arrangement shown in Fig. 9 is substantially the same as that shown in Fig. 5 and does not require further explanation herein.

It will be obvious that the details of construction and arrangement may be varied without departing from the spirit of the invention.

I claim as my invention—

1. In an automatic switch, the combination with a supporting-frame, of a shaft or drum, having a series of circuit-closers arranged thereon, journaled in the ends of said frame, a series of pairs of contacts carried by the 125 sides of said frame, one of the contacts of each of said pairs extending into the path of the circuit-closers, alternate pairs of contacts being carried by opposite sides of the frame, means for rotating the shaft or drum in one 130 direction, a detent engaging the shaft or drum to hold it with one of said circuit-closers in

position to press together one of the pairs of contacts, and means for releasing the detent; substantially as described.

2. In an automatic switch, the combination 5 with a supporting-frame of a shaft or drum, having a series of circuit-closers arranged thereon, journaled in the ends of said frame, a series of pairs of contacts each consisting of two terminals carried by the sides of said 10 frame, the terminals of one of the contacts of each of said pairs extending into the path of the circuit-closers, alternate pairs of contacts being carried by opposite sides of the frame, means for rotating the shaft or drum in one direction, a detent engaging the shaft or drum to hold it with the terminals of each of said 15 circuit-closers in position to press together a pair of contacts, and means for releasing the detent; substantially as described.
- 20 3. In an automatic switch, the combination with a supporting-frame, of a shaft or drum having a series of circuit-closers arranged thereon, journaled in the ends of said frame, a series of contacts carried by the sides of said 25 frame and extending into the path of the circuit-closers, alternate contacts being carried by opposite sides of the frame, an indicator-wheel carried by said shaft or drum between the ends of the supporting-frame and pro-

vided with a stop, means for rotating the shaft 30 or drum in one direction, a detent engaging the shaft or drum to hold it with one of said circuit-closers against one of said contacts, means for releasing the detent and a fixed stop on the supporting-frame in the path of 35 the stop carried by the indicator-wheel; substantially as described.

4. In an automatic switch, the combination with a supporting-frame, of a shaft or drum having a series of circuit-closers arranged 40 thereon, a series of contacts carried by the sides of said frame and extending into the path of the circuit-closers, an indicator-wheel having a rim adapted to bear designating characters, a stop extending inward from said 45 rim, means for rotating the shaft or drum in one direction, a detent engaging the shaft or drum to hold it with one of said circuit-closers against one of said contacts, means for releasing the detent, and a fixed stop in the path of 50 the stop carried by the indicator-wheel; substantially as described.

This specification signed and witnessed this 28th day of February, A. D. 1900.

LAMBERT SCHMIDT.
